UNITED STATES PATENT OFFICE.

LOUIS LEVIEN, OF SEA GATE, NEW YORK.

DESIGN FOR A TRAY FOR HOLDING GLASSES.

Application filed August 13, 1924. Serial No. 10,443. Term of patent 7 years.

To all whom it may concern:

Be it known that I, LOUIS LEVIEN, a citizen of the United States of America, residing at Sea Gate, in the county of Kings and State of New York, have invented a new, original, and ornamental Design for a Tray for Holding Glasses, of which the following is a specification, reference being had to the accompanying drawing, forming a part thereof.

In the drawing,

Figure 1 is a perspective view of the tray.
Figure 2 is a top plan view of the tray.
Figure 3 is a side view of the tray.

I claim:—

The ornamental design for a tray for holding glasses substantially as shown.

LOUIS LEVIEN.
